[57] CLAIM

The ornamental design for a salad server, as shown and described.

DESCRIPTION

FIG. 1 is a front view of a salad server showing my new design as embodied in a spoon;

FIG. 2 is a rear view thereof;

FIG. 3 is a side view thereof; the side opposite is identical to the side shown;

FIG. 4 is a top view thereof;

FIG. 5 is a bottom view thereof;

FIG. 6 is a sectional view thereof taken on the line 6—6 of FIG. 1;

FIG. 7 is a front view of a salad server showing my new design as embodied in a fork;

FIG. 8 is a rear view thereof;

FIG. 9 is a side view thereof; the side opposite is identical to the side shown;

FIG. 10 is a top view thereof;

FIG. 11 is a bottom view thereof;

FIG. 12 is a sectional view thereof taken on the line 12—12 of FIG. 7.
